UNITED STATES PATENT OFFICE.

DAVID M. GILBERT, OF NEW YORK, N. Y.

DESIGN FOR A HOOD FOR INCANDESCENT ELECTRIC LAMPS.

SPECIFICATION forming part of Design No. 37,450, dated May 30, 1905.

Application filed April 24, 1905. Serial No. 257,284. Term of patent 7 years.

To all whom it may concern:

Be it known that I, DAVID M. GILBERT, a citizen of the United States, and a resident of New York, in the county of New York and State of New York, have invented a certain new and useful Design for a Hood for Incandescent Electric Lamps, of which the following is a specification.

Figure 1 is a side elevation of my design, 10 and Fig. 2 is a plan view.

What I claim as new, and desire to secure by Letters Patent, is—

The ornamental design for a hood for incandescent electric lamps, as shown.

DAVID M. GILBERT.
